UNITED STATES PATENT OFFICE.

JOSEPH C. GASKILL, OF OSWEGO, NEW YORK, ASSIGNOR TO AMES IRON WORKS, OF OSWEGO, NEW YORK, A CORPORATION OF NEW YORK.

OIL AND WATER SEPARATOR.

SPECIFICATION forming part of Letters Patent No. 774,577, dated November 8, 1904.

Application filed March 23, 1904. Serial No. 199,596. (No model.)

To all whom it may concern:

Be it known that I, JOSEPH C. GASKILL, a citizen of the United States, residing at Oswego, in the county of Oswego and State of New York, have invented certain new and useful Improvements in Oil and Water Separators; and I do declare the following to be a full, clear, and exact description of the invention, such as will enable others skilled in the art to which it appertains to make and use the same.

This invention relates to oil and water separators; and it has for its object to provide a simple, durable, and comparatively inexpensive separator; and it consists of the parts and combinations of parts hereinafter described and claimed.

In the accompanying drawings, forming a part of this specification, Figure 1 is a vertical section of my improved oil and water separator; Fig. 2, an end view of the same; Fig. 3, a vertical section of a modified form of my invention; Fig. 4, an end view of the same, and Fig. 5 a vertical section of another modification of my invention.

Similar letters refer to similar parts throughout all the views.

Referring more particularly to Fig. 1 of the drawings, A represents a tank or vessel, preferably rectangular in shape, having a closed top and bottom and formed or provided with the flaring flange c at its top to form a hopper or receiving-chamber a for the mixed oil and water. From the lower or under side of the top of the tank or vessel a partition d extends vertically downward for a part of its length and then incliningly toward one side of the tank, as at d', and terminates at a point slightly above the bottom of the tank. A partition d' also extends from the under side of the top of the tank vertically downward parallel to and at a short distance from the partition d and terminates at a point above the end of the straight or unslanted part of the partition d, so as to provide a conducting-chamber B between said partitions, which communicates at its upper end with the receiving-chamber a through a slot or oblong opening a', formed in the top of the tank. By means of a

short vertical partition d² and a transverse partition d⁴, extending partly across the tank from the partition d, the conducting-chamber B is extended upwardly on itself and provides a discharge-chamber C, which opens into a separating-chamber D. The separating-chamber D is formed by the partitions d² d' and the contiguous wall of the tank, said separating-chamber D being provided with an outlet-opening e near its top. E is a vertical intermediate chamber formed by the partition d⁶ and a partition f, the latter extending from the bottom of the tank or vessel to a point near its top, but terminating below the outlet-opening e of the separating-chamber D. The partition f and the adjacent wall of the tank or vessel form an overflow-chamber F, which has communication with intermediate chamber E over the top of the partition f. An outlet-opening g is provided for the overflow-chamber F near its bottom. H is a tapped or plug opening formed in the bottom of the tank, whereby it may be cleansed of sediment.

This separator is designed, primarily, for the treatment of lubricating-oils, such as drippings from the bearings of steam-engines and machinery generally, so as to separate particles of foreign substances from the oil, and thus enable it to be again used as a lubricant, and the form above described presents a convenient and preferred embodiment of my invention; but I do not desire to be restricted to such form, as it is obvious good results may be obtained from modified constructions without departing from the spirit of my invention, and in Figs. 3 and 4 and 5 I have shown structural modifications which also embody my invention, as will be now described.

Referring to Figs. 3 and 4, A represents the tank, and a the receiving-chamber, the latter having communication through an oblong opening a² with a conducting-chamber B', formed by the adjacent wall of the tank, and a partition D², extending from the top of the tank downwardly and terminating at a point above a transverse partition D³ from the wall of the tank, which connects with a short vertical extension D⁴, which extends upwardly in said tank parallel with the partition D² and forms

a continuation of the conducting-chamber B^1 and provides a discharge-chamber C^1 , which opens upwardly into a separating-chamber D^1 . The separating-chamber D^1 is formed by the partitions D^2 , D^4 and the wall of the tank at one side and a partition E' , which extends from near the bottom of the tank to a point above the outlet e of the separating-chamber D^1 , near the top thereof, and said partition E' , with a partition F' , forming an intermediate chamber E^2 , which communicates with the separating-chamber D^1 through the passage-way under the partition E' and also has communication at its top over the partition F' with an overflow-chamber F^2 , formed by said partition F' and the contiguous wall of the tank. The partition F' extends from the bottom of the tank to a point near the top thereof below the outlet-opening of the separating-chamber D^1 , and an outlet-opening g is provided at or near the bottom of the overflow-chamber F^2 .

In Fig. 5 is shown another form of my invention, in which A' represents the tank, which may be partly open at its top, as at A^2 , and having the hopper-chamber a^4 at one side thereof. The tank A' is preferably cylindrical in shape, and the hopper-chamber communicates through an opening therein with a conducting-chamber B^2 , formed by a partition C^2 , extending downwardly from the top of the tank and the adjacent wall of the tank, the bottom of said conducting-chamber B^2 being formed by a transverse partition C^3 from the wall of the tank, which connects with a short vertical partition C^4 , so as to provide a continuation of the conducting-chamber B^2 and forming a discharge-chamber which opens upwardly into a separating-chamber E^3 , formed by the wall of the tank and a cylindrical partition F^3 , which extends downwardly from the top of the tank to a point near the bottom thereof and is connected to a central tube G , which provides an intermediate chamber H' , which extends upwardly from the bottom of the tank to a point near its top, but terminating below the plane of the outlet-opening e^3 . The separating-chamber E^3 has communication with the intermediate chamber H' , formed by the partition F^3 and the tube G , through the openings h at the bottom of said intermediate chamber, and the intermediate chamber H' has communication with the overflow-chamber H^3 , the wall of which is formed by the tube G , through the upper open end of said tube. An outlet-opening g' is provided at the bottom of the overflow-chamber H^3 , and

tapped or plug opening H^3 is provided at the bottom of the separating-chamber E^3 to provide for the removal of sediment or the cleansing of the tank.

In operation the oil and water is supplied to the hopper-chamber and passes therefrom to the conducting and discharge chamber, from which it is discharged upwardly into the separating-chamber. The oil being the lighter rises to the top of the water, and as the supply to the hopper continues the tank fills to the outlet-opening and the oil overflows therethrough. The water passes from the separating-chamber through the passage-way therefor to the intermediate chamber and rises therein until it overflows into the overflow-chamber and escapes therefrom through the outlet thereof. This operation continues as long as the supply of oil and water is maintained.

It will be observed that the oil and water passes from the hopper in sheet form or in a thin flat column and is delivered to the separating or oil-discharging chamber in an upward direction and in a thin sheet, thus facilitating the separation of the oil and water.

Having thus described my invention, what I claim as new, and desire to secure by Letters Patent, is—

An oil and water separating tank constructed with a top having an opening and a flange providing a receiving-chamber, a transverse partition extending partly across the tank having an upward vertical extension, a depending partition located between the opening and the upward vertical extension and extending downward to a position adjacent to the transverse partition and providing a vertical conducting-chamber on one side of the depending partition, a transverse passage beneath the lower end thereof and a short vertical discharge-chamber parallel with the conducting-chamber on the other side of the depending partition, a separating-chamber with which the discharge-chamber communicates having an oil-outlet at its upper end, an intermediate chamber with which the latter communicates at the lower end, an overflow-chamber with which the intermediate chamber communicates at a lower level than the oil-outlet, and an outlet to the overflow-chamber.

In testimony whereof I affix my signature in presence of two witnesses.

JOSEPH C. GASKILL.
